G. B. TREW.
PIPE WRENCH.
APPLICATION FILED AUG. 28, 1920.

1,388,079.

Patented Aug. 16, 1921.

UNITED STATES PATENT OFFICE.

GEORGE BARNETTE TREW, OF SHREVEPORT, LOUISIANA, ASSIGNOR OF ONE-HALF TO
S. A. GUIBERSON, JR., OF LOS ANGELES, CALIFORNIA.

REISSUED

PIPE-WRENCH.

1,388,079.

Specification of Letters Patent. Patented Aug. 16, 1921.

Application filed August 28, 1920. Serial No. 406,546.

To all whom it may concern:

Be it known that I, GEORGE B. TREW, a citizen of the United States, residing at Shreveport, in the county of Caddo and 5 State of Louisiana, have invented a new and useful Pipe-Wrench, of which the following in a specification.

The device forming the subject matter of this application is a wrench, adapted to handle a pipe or other piece of material which 10 is circular in cross section, and one object of the invention is to provide novel means whereby a grip portion of the wrench may be held in closed position with respect to the 15 material.

Another object of the invention is to provide novel means for operating and controlling the jaws which engage the material.

A further object of the invention is to 20 provide novel means whereby the material cannot be crushed or marred by the jaws.

It is within the province of the disclosure to improve generally and to enhance the 25 utility of devices of that type to which the invention appertains.

With the above and other objects in view, which will appear as the description proceeds, the invention resides in the combination and arrangement of parts and in the 30 details of construction hereinafter described and claimed, it being understood that, within the scope of what is claimed, changes in the precise embodiment of the invention shown can be made without departing from 35 the spirit of the invention.

In the accompanying drawings:—

Figure 1 shows in side elevation, a wrench 40 constructed in accordance with the invention, parts being broken away; Fig. 2 is an elevation wherein the wrench is viewed edge-wise.

The wrench comprises a forked head including an arm 2 and an arm 3, the arm 3 having a lateral projection 30. The arm 2 45 terminates in bifurcations 4, the arm 3 terminating in bifurcations 5. The head 1 has ears 6, one ear being supplied in its end with a seat or notch 60. The head 1 has an opening 7 communicating with the space between 50 the ears 6.

The numeral 8 designates an arcuate grip, one part 9 of which is located between the bifurcation 4 of the arm 2. The grip 8 is 55 connected to the bifurcations 4 by a pivot element 10. A curved spring 11 is connect-

ed at one end 12 to the part 9 of the grip 8 relatively near to the pivot element 10, the spring 11 extending inwardly. The free end 14 of the grip 8 extends between the bifurcations 5 and is provided with a transverse shoulder 15.

The numeral 16 denotes a latch having an opening 17 wherein the shoulder 15 of the grip 8 is received, the shoulder coöperating with the latch at one end of the opening 17. 65 The latch 16 is beveled as indicated at 18 and defines an acute angle with the adjacent portion of the grip 8. Because the latch 16 is beveled as indicated at 18, the grip 8 will engage automatically with the latch 70 when the grip is swung to a closed position, and because the end of the latch 16 defines an acute angle with the adjacent portion of the grip, the finger of an operator may be inserted readily between the end of the latch 75 and the grip, to disengage the latch from the grip. The rear end of the latch 16 is tapered as indicated at 19, a spring 90 being interposed between the said end of the latch 80 and the arm 3 of the head 1. The spring 90 tends to maintain the latch 16 engaged with the shoulder 15 on the grip 8. The latch 16 is pivotally mounted, as indicated at 75, on the projection 30 of the arm 3 and terminates in a thumb piece 20, facilitating the 85 manipulation of the latch.

Jaws 21 are mounted for limited reciprocation in the opening 7 of the head 1, in contact with the outer edges of the opening. The jaws 21 are supplied with elongated slots 90 22, through which extend pins 23, the ends of the pins being mounted in the head 1. The teeth 24 of the jaws 21 slope in opposite directions, to facilitate the holding of the work, when the wrench is swung in one direction or in an opposite direction.

A fulcrum bolt 25 is carried by the ears 6 of the head 1. The numeral 26 denotes a handle having an enlargement 27 mounted to swing on the fulcrum bolt 25 and located 100 between the ears 6. On the inner end of the enlargement 26 are cam surfaces 28, each of which is adapted to coöperate with the inner end of one of the jaws 21. A T-shaped dog 29 is pivoted at 30 to the handle 26 and 105 is adapted to coact with the seat 60, in a way to be pointed out hereinafter.

When the article which is to be rotated is inserted between the arms 2 and 3 of the head 1, and when the grip 8 is swung to a 110

closed position, the piece of material engages the spring 11 and tends to hold the grip in a closed position until the grip has been advanced far enough toward a completely closed position, so that the latch 16 under the impulse of the spring 90, engages the shoulder 15 of the grip, and holds the grip closed, as hereinbefore set forth.

When the handle 26 is manipulated, to 10 turn the object, the handle swings on the fulcrum bolt 25. One of the cam surfaces 28 coöperates with the corresponding jaw 21, and advances the jaw to cause the jaw to grip the object which is to be rotated. If 15 the handle 26 is swung in one direction, then one of the jaws 21 will be actuated, whereas, if the handle is swung in an opposite direction, the other of the jaws will be actuated. The dog 29 may be swung on its pivotal 20 mounting 30, so that one end or the other of the dog will be received in the seat 60. When the handle 26 has tilted or swung an appreciable amount, on the fulcrum bolt 25, the dog, engaging with the rear end of the 25 ear, at one end of the seat 60, prevents further swinging movement of the handle. As a consequence, the jaw 21 can be advanced a predetermined amount only, and it will be practically impossible to crush the object 30 which is being turned, or to mar the object to an undesirable extent.

Having thus described the invention, what is claimed is:

1. A wrench comprising a head having 35 arms; a grip extended between the arms; jaws slidable in the head; and a handle ful-

crumed on the head and having cams engaging the jaws.

2. A wrench comprising a loop-shaped head; jaws slidable in the head and shaped 40 at their inner ends for engagement with the object to be rotated; and a handle fulcrumed on the head and having cams engaging the outer ends of the jaws, to advance one jaw at a time, when the handle is swung 45 in opposite directions.

3. A wrench comprising a head having arms; a grip extended between the arms, the grip being pivoted at one end to one arm; a latch mounted on the other arm and interlocked with the other end of the grip, the first specified end of the grip being provided with an inwardly projecting spring adapted 50 to engage the work; jaws slidable in the head; and a handle fulcrumed on the head 55 and having cams engaging the jaws.

4. A wrench comprising a head having arms; a grip extended between the arms; jaws slidable in the head; a handle fulcrumed on the head and having cams engaging the jaws; and a dog movably mounted 60 on the handle and engageable with the head to limit the swinging movement of the handle, and to limit the advancement of the jaws.

In testimony that I claim the foregoing as my own, I have hereto affixed my signature in the presence of two witnesses.

GEORGE BARNETTE TREW.
